CLAIM

The ornamental design for a receptacle for optic and electrical hybrid connector, as shown and described.

DESCRIPTION

FIG. 1 is a front perspective view of a receptacle for optic and electrical hybrid connector of a first embodiment of the present invention;

FIG. 2 is another front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof

FIG. 9 is a front perspective view of a receptacle for optic and electrical hybrid connector of a second embodiment of the present invention;

FIG. 10 is another front perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines show parts of the receptacle for optic and electrical hybrid connector that represent unclaimed subject matter and form no part of the claimed design. Additionally, the dot-dash lines shown in FIGS. 10 and 11 define the limits of the claimed design
